COMBINED PORTABLE SEAT AND CAMERA SUPPORT

Joseph M. Harris, 1010 Lexington Road,
Beverly Hills, Calif.

Filed Dec. 18, 1961, Ser. No. 67,930

Term of patent 7 years

(Cl. D15—8)

FIGURE 1 is a perspective view of a combined portable seat and camera support embodying my design, with the seat shown in open position and the support in extended position;

FIG. 2 is a side elevation thereof;

FIG. 3 is a plan view thereof;

FIG. 4 is a side elevation of the support and seat, with the seat shown in closed position and the support in collapsed position; and

FIG. 5 is a sectional detail of the lower portion of the support showing the detachable end portion in store position.

The broken lines indicating a camera shown in the drawings are for illustrative purposes only.

I claim:

The ornamental design for a combined portable seat and camera support, substantially as shown and described.
